UNITED STATES PATENT OFFICE.

ALEXANDER McLAREN, OF CHICAGO, ILLINOIS.

DESIGN FOR AN ICE-CREAM CONE.

• 54,439.

Specification for Design.

Patented Feb. 10, 1920.

Application filed September 3, 1919. Serial No. 321,476. Term of patent 14 years.

To all whom it may concern:

Be it known that I, ALEXANDER McLAREN, a citizen of the United States, residing at Chicago, in the county of Cook and State of Illinois, have invented a new, original, and ornamental Design for Ice-Cream Cones, of which the following is a specification, reference being had to the accompanying drawing, forming a part thereof.

Figure 1 is a top plan view of an ice cream cone showing my new design.

Fig. 2 is a side elevation of the same.

I claim:

The ornamental design for an ice cream cone substantially as shown.

ALEXANDER McLAREN.
